VENT DEVICE

Leroy J. Thompson, Grand Rapids, Mich.

Application January 21, 1933. Serial No. 652,952

13 Claims. (Cl. 217—105)

This application is related to my copending application Serial No. 514,564, filed February 9, 1931, for vent devices for fermenting receptacles.

The objects of this invention are:

First, to provide a simple and effective vent device for use in fermentation.

Second, to provide such a device that can be easily installed in the bung of a keg or barrel and which will provide a water seal.

Third, to provide such a device in which there is a check valve to prevent drawing back of the water seal into the barrel or keg.

Fourth, to provide such a device that may be molded of rubber or suitable composition material and in which the check valve may be easily and cheaply constructed and installed to produce a unitary structure.

Other objects and advantages pertaining to details and economies of construction and operation will appear from the description to follow.

A preferred embodiment of my invention is illustrated in the accompanying drawing, in which:

Fig. 1 is a view partly in section of my improved device taken on line 1—1 of Fig. 2.

Fig. 2 is a plan view of my device.

Fig. 3 is a view partly in section of the U-tube and check valve arrangement.

Fig. 4 is a sectional view of a modified form of my device.

The parts will be identified by their numerals of reference which are the same in all the views.

1 is the body portion that is formed of molded rubber or any suitable composition material or wood. A suitable material illustrated in Fig. 4 is sawdust made into a plastic mass with glue or rubber cement and molded or turned out on a lathe or the like. 2 is a stopper portion thereon for insertion in the bung of a keg or barrel. 3 is the seal chamber in which water or a suitable fluid 4 may be placed as shown in Fig. 1 to effect sealing.

5 is a web extending into the seal chamber. The web here illustrated is substantially radial and has its inner end 6 spaced from the bottom of the seal chamber 3. The body portion is notched as at 7 and a bore 8 runs from the notch through the web opening into the seal chamber at the inner end of the web. 9 is a bore substantially parallel to the bore 8 running from the notch 7 to the stopper portion 2 to provide a vent from the inside of the keg. 10 is a U-tube adapted to have its legs 11 and 12 fitted in the bores 8 and 9 and to have its bight 13 fitted within the notch 7 so as to come below the end of the body portion 1 to pre-

vent injury to the tube. It is not necessary that the tube extend below the end of the body portion 1, but it is desirable and advantageous.

Associated with one leg of the tube 10 is a check valve construction that is adapted to fit within one of the bores. This is shown as a vented cap 14 fitting and soldered over the leg 12 of the U-tube 10 so as to leave a chamber 15 in which a ball 16 is loosely disposed to close the vent 17 in the cap 14 to prevent the fluid 4 from being sucked into the cask when pressure within the cask is reduced. At 18 is an overflow vent for the seal chamber 3. This vent may be omitted if desired.

Although I have shown a web through which the bore 8 extends, it will be obvious to those skilled in the art that the bores 8 and 9 can be in the body portion 1 without having any web formed extending into the seal chamber, it being only necessary to have one bore extend through the stopper portion to the keg and the other bore 65 through the body portion to communicate with the seal chamber at a point below the desired water level in the chamber.

In Fig. 4 I show a modified form of the device. The body 2 is shown formed of a sawdust and glue or rubber cement composition. A web 33 extends into the seal chamber having its top above the level of the liquid in the seal chamber. A bore 29 runs from the stopper portion 2 to the top of web 33 where it opens above the level of the fluid in the seal chamber, thus insuring against leakage of said fluid back to the barrel or keg. A U-tube 30 has one leg 31 disposed in said bore 29 and the other leg 32 is disposed in the seal chamber and opens therein. The tube 30 is recurved slightly as at 34 and is cut on the bias to form an upwardly facing or slanting valve seat 35. 36 is the valve body which is hinged or pivoted as at 37 to a web 38 on the tube. Gravity holds the valve closed.

My structure is especially adapted to be made of molded rubber or other suitable plastic material. A single operation is then necessary to form practically the whole structure while the U-tube 10 with its simple check valve construction is then easily installed and becomes a permanent part of the entire unit. It will be seen that a valve similar to that shown in Fig. 4 could be used in the other modification of my device.

Having thus described my invention, what I claim as new and desire to secure by Letters Patent is:

1. A vent device comprising a substantially cylindrical molded rubber body having a stopper portion at one end, a seal chamber at the other 110

end, and an integral web extending substantially radially into said seal chamber and having its inner end spaced from the bottom thereof, said body portion having a notch extending into said web, and a bore from said notch to the inner end of said web and a second bore from said notch to and through said stopper portion, and a U-tube having a check valve associated therewith comprising a vented cap disposed on one leg of said U-tube and a ball retained loosely between said cap and said leg, said U-tube having a leg fitted in each of said bores and its bight disposed in said notch.

15 2. A vent device comprising a molded rubber body having a stopper portion at one end, a seal chamber at the other end, and a web extending into said seal chamber and having its inner end spaced from the bottom thereof, said body portion having a notch and a bore from said notch to the inner end of said web and a second bore from said notch to and through said stopper portion, and a U-tube having a check valve associated therewith comprising a vented cap disposed on one leg of said U-tube and a ball retained loosely between said cap and said leg, said U-tube having a leg fitted in each of said bores and its bight disposed in said notch.

30 3. A vent device comprising a body having a stopper portion at one end, a seal chamber at the other end, and a web extending into said seal chamber and having its inner end spaced from the bottom thereof, said body portion having a notch and a bore from said notch to the inner end of said web, and a second bore from said notch to and through said stopper portion, and a U-tube having a check valve associated therewith comprising a vented cap disposed on one leg of said U-tube and a ball retained loosely between said cap and said leg, said U-tube having a leg fitted in each of said bores and its bight disposed in said notch.

4. A vent device comprising a molded rubber body having a stopper portion at one end, a seal chamber at the other end, and a web extending into said seal chamber and having its inner end spaced from the bottom thereof, said body portion having a notch extending into said web and a bore from said notch to the inner end of said web and a second bore from said notch to and through said stopper portion, and a U-tube having a check valve associated therewith and having a leg fitted in each of said bores and its bight disposed in said notch.

posed in said notch.

5. A vent device comprising a body having a
55 stopper portion at one end, a seal chamber at
the other end, and a web extending substan-
tially radially into said seal chamber and hav-
ing its inner end spaced from the bottom there-
of, said body portion having a notch and a bore
60 from said notch to the inner end of said web
and a second bore from said notch to and through
said stopper portion, and a U-tube having a
check valve associated therewith and having a
leg fitted in each of said bores.

65 leg fitted in each of said bores.

6. A vent device comprising a molded rubber body having a stopper portion at one end, a seal chamber at the other end, said body portion having a notch and a bore from said notch to said seal chamber and a second bore from said notch to and through said stopper portion, and a U-tube having a check valve associated therewith comprising a vented cap disposed on one leg of

said U-tube and a ball retained loosely between said cap and said leg, said U-tube having a leg fitted in each of said bores and its bight disposed in said notch.

7. A vent device comprising a body having a stopper portion at one end, a seal chamber at the other end, said body portion having a notch and a bore from said notch to said seal chamber and a second bore from said notch to and through said stopper portion, a U-tube having a check valve associated therewith comprising a vented cap disposed on one leg of said U-tube and a ball retained loosely between said cap and said leg, said U-tube having a leg fitted in each of said bores and its bight disposed in said notch. 80 85 90

8. A vent device comprising a body having a stopper portion at one end, a seal chamber at the other end, said body portion having a notch and a bore from said notch to said seal chamber and a second bore from said notch to and through said stopper portion, and a U-tube having a check valve associated therewith and having a leg fitted in each of said bores and its bight disposed in said notch. 100
35

9. A vent device comprising a molded rubber body having a stopper portion at one end, a seal chamber at the other end, said body portion having a bore to said seal chamber and a second bore extending to and through said stopper portion, and a U-tube having a check valve associated therewith comprising a vented cap disposed on one leg of said U-tube and a ball retained loosely between said cap and said leg, said U-tube having a leg fitted in each of said bores. 110

10. A vent device comprising a body having a stopper portion at one end, a seal chamber at the other end, said body portion having a bore extending to said seal chamber and a second bore extending to and through said stopper portion, and a U-tube having a check valve associated therewith comprising a vented cap disposed on one leg of said U-tube and a ball retained loosely between said cap and said leg, said U-tube being also fitted in each of said bores. 120

1 having a leg fitted in each of said bores. 120
1 11. A vent device comprising a body having a
1 stopper portion at one end, a seal chamber at
1 the other end, said body portion having a bore
1 extending to said seal chamber and a second
1 bore extending to and through said stopper por- 125
1 tion, and a U-tube having a check valve asso-
1 ciated therewith and having a leg fitted in each
1 of said bores.

12. A vent device comprising a molded rubber body having a stopper portion at one end, a seal chamber at the other end, and a web extending into said seal chamber and having its inner end spaced from the bottom thereof, said body portion having a notch and a bore from said notch to the inner end of said web and a second bore from said notch to and through said stopper portion, and a U-tube having a leg fitted in each of said bores and its bight disposed in said notch. 130 135

13. A vent device comprising a body having a stopper portion at one end, a seal chamber at the other end, said body portion having a notch and a bore from said notch to said seal chamber and a second bore from said notch to and through said stopper portion, and a U-tube having a leg fitted in each of said bores and its bight disposed in said notch. 140 145
